UNITED STATES PATENT OFFICE.

CHARLES L. DE MARTIN, OF CONNERSVILLE, INDIANA, ASSIGNOR TO INDIANA LAMP COMPANY, OF CONNERSVILLE, INDIANA, A CORPORATION.

ELECTRIC HEADLIGHT CONTROL.

1,314,639

Specification of Letters Patent. Patented Sept. 2, 1919.

Application filed April 1, 1918. Serial No. 225,987.

To all whom it may concern:

Be it known that I, CHARLES L. DE MARTIN, a citizen of the United States, and a resident of Connerville, county of Fayette, 5 and State of Indiana, have invented a certain new and useful Electric Headlight Control; and I do hereby declare that the following is a full, clear, and exact description thereof, reference being had to the accompanying drawings, in which like letters refer to like parts.

The object of this invention is to improve the construction and operation of headlights for automobiles, launches and the like, 15 wherein there is a tilting reflector, and wherein said tilting reflector is operated or controlled by means utilizing the partial vacuum or suction in the intake manifold or other chamber in communication with the 20 cylinders of an internal combustion engine. This invention is made with particular reference for use in connection with what are known as "Ford" headlights, but it may also be used in connection with other headlight 25 constructions.

One feature of the invention consists in mounting the cylinder for utilizing the partial vacuum or suction, outside and to the rear of the lamp casing. In lamps of this 30 type, the casing is relatively small and there is no relatively great space between the casing and the reflector and with this feature of the invention, said cylinder for utilizing the partial vacuum or suction to operate the 35 reflector can be attached to such lamps already made and makes a special construction of the lamp needless. This gives to the invention great practical value.

Another feature of the invention consists 40 in the means for connecting the piston of the vacuum cylinder with the reflector. Since such cylinder is located out of the lamp casing, the piston must extend through a small hole bored in the lamp casing and 45 special means must be provided for connecting or coupling the inner end of the piston with the reflector, when it cannot be seen or manipulated. To that end, means is secured to the reflector adapted to engage the 50 inner end of the piston when the latter is pushed into place, and so that it can be disengaged by merely withdrawing the piston.

Another feature of the invention consists 55 in mounting the vacuum cylinder so that it

can be adjustable toward or away from the lamp casing for the purpose of permanently changing the normal position of the reflector and thus changing the focus. This is a very important feature of the invention as 60 it enables one to permanently adjust the direction of light from the lamp and so that it can still be temporarily adjusted by the vacuum control.

Another feature of the invention consists 65 in the means for mounting the vacuum cylinder; in the form of a bracket, fitting against and secured to the flat rear end or surface of the lamp case around the connection or socket member at the rear end of the 70 lamp case.

The full nature of the invention will be understood from the accompanying drawings and the following description and claims:

In the drawings, Figure 1 is a central vertical section through the lamp with the parts in inoperated and unadjusted position. Fig. 2 is the same with the suction cylinder adjusted so that the piston rod 80 holds the reflector normally in a tilted position so as to change the direction of the rays of the lamp. Fig. 3 is the same with the suction apparatus operated so as to tilt the reflector more than in Fig. 2. Fig. 4 85 is a section on the line 4—4 of Fig. 1. Fig. 5 is a rear elevation of a portion of the lamp showing the mounting of the vacuum cylinder, the lamp casing being partially broken away. Fig. 6 is a central vertical 90 section through the rear portion of the lamp casing and associated parts, parts being broken away. Fig. 7 is a radial section through a portion of the lamp structure showing the connection between the lamp 95 casing, door, lens, reflector and reflector ring, on an enlarged scale. Fig. 8 is a front elevation of a portion of the lamp casing and the reflector ring in locking position, parts being broken away.

The Ford lamp has a casing 10 shaped like the end of an ellipse, the apex being flattened at 11 where the rearwardly extending socket housing 12 is secured.

The lamp has at its front end the usual 105 lens 13 which is held in by a ring 14 which is mounted in a door of the lamp by clips 15. The door has inwardly-extending lugs 16 which enter slots in the front portion of the lamp casing, whereby the door is held 110

in place. A lens bears and presses against a cord packing 17 on the reflector ring 18 which is removably mounted in the front part of the casing and bears against spring fingers 19.

- 5 A reflector 20 is hinged at its upper portion to the reflector ring 18 by a pivot or hinge 21, so that the reflector is suspended and can tilt backward or forward, as shown.
- 10 The invention, however, is not limited to any particular mounting of the reflector or arrangement thereof so long as the reflector is movable or tiltable. A lamp 22 is secured in a socket 23 in the rear central portion of
- 15 the reflector and a suitable insulating wiring connection 24 is provided whereby the current is supplied to the lamp. The lamp on the whole is supported on the automobile by a single arm or post 25 which at its upper end is secured to a plate 26 having four radiating arms that are riveted to the casing of the lamp.

In order to equip an ordinary Ford lamp or the like with this invention, the old reflector is removed and the reflector construction shown herein, including reflector ring 18 and reflector 20 hinged thereto, is substituted. Also the focusing device found in such lamps is also removed and in place thereof the socket and socket housing 12 are secured, the inner end of the housing 12 having a flaring plate which is fastened to the flat portion of the casing by the screws 27. Also a hole 28 has to be drilled in the casing for the piston rod 30 when the reflector is actually controlled by the means herein shown.

- 30 The reflector actuating and controlling means is then added to the lamp and the form thereof herein disclosed is as follows:
- 35 40 A vacuum cylinder 31 is adjustably mounted in a clamping member 32 that is connected with the bracket 33. The upper portion of this bracket is circular and surrounds the socket housing 12 and is secured to the flat portion of the lamp casing by the screw 27. The clamp 32 is held tight by a screw 34, see Fig. 5. The vacuum cylinder 31 is connected by a small pipe or conduit 36 with the manifold of an internal combustion engine or other means for creating a vacuum in said cylinder so as to cause the withdrawal or operation of the piston 37 in the cylinder, as shown in Fig. 3. Such movement of the cylinder, through the piston rod 30 draws backward the lower end of the reflector 20 and tilts it so as to change the focus or direction of the shaft of light from the lamp. The piston is returned to its normal position, as shown in Fig. 1, by 45 a spring 38 within the cylinder.

60 The piston rod 30 can be connected in any desired way with the reflector, but it should be in such way as to enable the connection to be made without either seeing the connecting parts or manipulating them. In

other words, the piston 30 is inserted through the hole 28 and in the forms here shown the inner end of the piston rod is a ball 39, that is forced between a pair of spring metal plates 40 secured to the underside of the reflector and having oppositely located holes 41 therein into which the ball of the piston rod seats itself. The friction between the ball 39 and the plates 41 is sufficient to maintain the connection 75 and yet permit the separation of the piston rod by its forcible withdrawal and, as stated above, permit the connection to be established by the forcible insertion of the piston rod.

80 One feature of the invention consists in the connection between the reflector 20 and reflector ring 18 and the shape of the latter so that no dust or water can enter the lamp behind the reflector. To make such joint, 85 the internal diameter of the outer edge of the reflector is greater than and overlaps the inner edge of the reflector ring 18, and the ring is transversely offset, as shown in cross section, toward the front so as to 90 deflect dust and water to the front and protect the reflector. Also the ring 18 is provided with a groove or annular seat into which the flange of the reflector is seated to the rear of the ring.

95 In order that the reflector when put in the lamp may be positioned to cause the spring holders to register with and properly receive the enlarged end of the piston rod when it is inserted through the hole 28 in 100 the casing, there are stop lugs 50 on the reflector ring 18 adapted to engage stamped in lugs 51 on the lamp casing as said ring is given angular movement. The details of this construction are indicated in Fig. 8.

105 This invention, therefore, is rigidly attached to an ordinary lamp of the Ford type and when so attached, affords a tilting reflector with all of its advantages and a satisfactory means for operating and controlling the reflector, by utilizing the partial vacuum or suction in the manifold or some part of the engine.

110 The invention claimed is:

1. A lamp having a casing, a reflector mounted therein so as to be tiltable, a fluid actuated means mounted outside of the casing, a rod connected with said fluid actuated means and extending loosely through the casing, and means whereby said rod may be insertibly connected with the reflector for actuating the same and disengaged by withdrawing it therefrom.

- 120 2. A lamp having a casing with a flattened rear surface, a reflector mounted in said casing so as to be tiltable, a bracket secured to the outer surface of the flattened portion of the lamp casing, a vacuum cylinder carried by said bracket outside of the lamp casing, and a piston rod extend-

ing from said cylinder loosely through said vacuum casing and connected with the reflector for operating and controlling it.

2. A lamp having a lamp casing, a reflector tiltably mounted therein, a socket housing extending centrally from the rear portion of said casing, a bracket surrounding said housing and secured to the casing, a vacuum cylinder carried by said bracket outside of the lamp casing, and a piston rod extending from said cylinder loosely

through said vacuum casing and connected with the reflector for operating and controlling it.

In witness whereof, I have hereunto affixed **15** my signature in the presence of the witnesses herein named.

CHARLES L. DE MARTIN.
